UNITED STATES PATENT OFFICE

100,686

DESIGN FOR A PASTE TUBE

Simon De Vaulchier, New York, N. Y., assignor
to Colgate-Palmolive-Peet Company, Jersey
City, N. J., a corporation of Delaware

Application April 17, 1935, Serial No. 56,436

Term of patent 14 years

To all whom it may concern:

Be it known that I, Simon De Vaulchier, a citizen of France, residing at the Vanderbilt Hotel, Park Avenue and 34th Street, New York city, county and State of New York, have invented a new, original, and ornamental Design for a Paste Tube, of which the following is a specification, reference being had to the accompanying drawing, forming a part thereof.

Fig. 1 is a top plan view of a paste tube with cap showing my new design;

Fig. 2 is a side elevational view thereof;

Fig. 3 is an end elevational view thereof;

Fig. 4 is an enlarged fragmentary side eleva-

tional view of the top portion of the tube; and
Fig. 5 is a top plan view of the tube with the cap removed.

The dominant feature of my invention resides in the combined design effect produced by the concentric steps on the conical top surface of the tube and the fluting of the vertical wall of the cap surmounted by the dome-like smooth surface of the cap top, as more particularly shown in Figures 1 and 2.

I claim:

The ornamental design for a paste tube as shown and described in the specification.

SIMON DE VAULCHIER.
